UNITED STATES PATENT OFFICE.

WALDEMAR W. FROESCHLE, OF ST. LOUIS, MISSOURI, ASSIGNOR TO CHARLES J. GREGORY, OF ST. LOUIS, MISSOURI.

ANATOMICAL SUPPORT.

Application filed August 15, 1921. Serial No. 492,372.

To all whom it may concern:

Be it known that I, WALDEMAR W. FROESCHLE, a citizen of the United States, residing at city of St. Louis, State of Missouri, have invented a certain new and useful Improvement in Anatomical Supports, of which the following is a full, clear, and exact description, such as will enable others skilled in the art to which it appertains to 10 make and use the same, reference being had to the accompanying drawings, forming part of this specification.

My invention relates to anatomical supports such as are used for correcting foot 15 deformities and consists in an improved support for longitudinal and transverse metatarsal arches.

One object of my invention is to provide 20 pockets for holding removable inserts which will permit the wear to come exclusively on the insert and prevent wearing of the edges of the pockets.

An additional object of my invention is to provide a single pocket adapted to receive 25 and hold a relatively small insert in different positions in the pocket.

Another object of my invention is to prevent the rear end of the support from curling up around the heel of the wearer thereby 30 moving the support longitudinally of the wearer's foot and thereby displacing the supporting points of the support from their desired position.

Still another object of my invention is to 35 enable one insert to be used in different positions thereby eliminating the number of inserts necessary to be carried in stock by the retailer or to be purchased by the consumer.

40 In the accompanying drawings which illustrate a selected embodiment of my invention,

Figure 1 is a bottom view of my support.

45 Figure 2 is a longitudinal vertical section through the same.

Figures 3 and 4 are, respectively, plan and sectional views of one of the inserts used with my support.

50 The body of the arch comprises a piece of flexible although relatively heavy leather 1 adapted to extend from the heel to the front of the metatarsal arch of the wearer. This body is reinforced near its middle by a leather strip 2.

55 Supports of this type, when worn, have a

tendency to curl upward at the rear which is at once uncomfortable and dislodges the supporting points. To prevent this, I secure a flat piece of light stiff metal 3 to the rear end of the body 1. This strip 3 is 60 shown attached by a flat head rivet 4 but obviously may be assembled with the body by being inserted in a slit or by other suitable methods.

Covering the bottom of the support is a 65 relatively thin sheet of leather 5, stitched to the body, as indicated by dash lines 6 and 7. It will be noted that the lines of stitching 7 form an irregular oval. On substantially the major axis of this oval, 70 strip 5 is cut away, as indicated at 8, to provide an oval opening therein which forms two opposed arcuate pockets 9 and 10 having a common chord substantially aligned with the major axis of the opening and of 75 stitching 7.

The insert 11 to be positioned in pockets 9 and 10 is detailed in Figures 3 and 4 and 80 preferably consists of an oval plug of rubber highest at the center and tapering therefrom towards each edge. This plug may be inserted in pockets 9 and 10, as indicated by solid lines in Figure 1, or in either end of the pockets as suggested by the dot and dash line in Figure 1. When inserted in 85 the center, the major axis of the oval insert is positioned transversely of the major axis of the opening and the ends of the plug extend to near the rear of the pockets in opposite directions thereby holding the plug 90 in desired position. When inserted in the end of the pocket the transverse axis of the plug is positioned transversely of the major axis of the opening and here again the edges of the plug extend in opposite directions to 95 the rear end of the pockets.

It is obvious that by rotating plug 11, it may be held fairly securely with its highest point at any desired point in the major axis of the opening.

100 It will be understood that the major axis of opening 8 corresponds to the axis of the transverse metatarsal arch of the wearer's foot and this shifting of the plug enables the wearer to support any one of the metatarsal bones requiring adjustment.

Irrespective of the position of insert 11 in pockets 9 and 10, the highest point of the insert and accordingly the point of greatest wear is in the opening 8. The arcuate sides 110

of the opening free the edges of strip 5 from wear and greatly prolong the usefulness of the support.

It will be noted that the pad 12 which 5 may be used to support the longitudinal metatarsal arch has its highest point nearer one end than the other whereby it may be reversed and thereby shift the longitudinal position of its supporting point. This enables the use of a single pad to secure at 10 least two different effects in the use of the support.

I claim:

1. In an anatomical support of the class 15 described, a body, opposed shallow pockets therein, and a removable insert provided with tapering edges inserted in said pockets and a relatively thick supporting portion extending substantially entirely beyond said 20 pockets.

2. In an anatomical support, opposed arcuate pockets positioned so that the shortest line from any point at the bottom of one pocket to the bottom of the other pocket 25 varies in length from similar lines drawn from other points at the bottom of either pocket, and a supporting insert having varying diameters corresponding in length to the above-mentioned lines, whereby rotating the insert in the pockets opposite edges of the insert will engage the bottoms of the pockets to retain the central part of the insert in any desired position.

3. In an anatomical support of the class 30 35 described, a body member, a flexible member secured thereto along spaced lines and a substantial opening in said member between said lines surrounded by flaps of said

member extending inwardly from said lines, and a shiftable insert positioned in said 40 opening and held thereby by engagement near its edges only by the spaced flaps of said member.

4. In an anatomical supporting device, a body, a flexible member, an oval line of 45 stitching uniting said body and member, an oval opening in said member substantially smaller in area than the area enclosed by said oval line of stitching, and a removable insert having opposite edges secured 50 between said body and member at opposite sides of said opening, and having a supporting portion located in said opening.

5. In an anatomical supporting device, a body, a flexible member, an oval line of 55 stitching uniting said body and member, an oval opening in said member substantially smaller in area than the area enclosed by said oval line of stitching, and an oval insert adapted to be positioned transversely 60 of the middle portion of said opening or to be positioned longitudinally of said opening at either end thereof and having a supporting portion which will be located at said opening when the insert is in either 65 position.

6. In an anatomical support, opposed arcuate pockets positioned so that they have a common chord which extends along the 70 anterior metatarsal arch of the wearer, and a removable supporting insert adapted to be retained by said pockets at any point along said chord.

In testimony whereof I hereunto affix my signature this 28th day of July, 1921.

WALDEMAR W. FROESCHLE.
